[57] CLAIM

The ornamental design for a desk organizer, as shown and described.

DESCRIPTION

FIG. 1 is a perspective view of a desk organizer showing our new design;

FIG. 2 is a left side elevational view, the opposite side being a mirror image thereof;

FIG. 3 is a bottom plan view;

FIG. 4 is a top plan view;

FIG. 5 is a front elevational view; and

FIG. 6 is a rear elevational view thereof;

FIG. 7 is a perspective view of a second embodiment showing my new design;

FIG. 8 is a top plan view;

FIG. 9 is a front elevational view; and

FIG. 10 is rear elevational view thereof.

The side and bottom views of the second embodiment shown in FIG. 7 are substantially the same as those shown in FIGS. 2 and 3 respectively.
